SCALE AND CHART THEREFOR

Filed April 8, 1925

2 Sheets-Sheet 2

Fig. 3. A top-down view of a rectangular baking tray (22) with a fluted edge. Inside, there are three layers of diagonal hatching. The top layer is labeled "SPONGE CAKE" and contains the following instructions: "BEAT EGG WHITES UNTIL STIFF", "MIX WELL", and "BAKE IN THREE LAYERS". The middle layer is labeled "[P-BAKING POWDER]". The bottom layer is labeled "[P-ORANGE JUICE]". The tray has dimensions: 22 (width), 23 (depth), 26 (width of the fluted edge), 27 (depth of the fluted edge), and 30 (width of the base). Labels 15, 17, and 19 are also present.

Fig. 4. A side view of the tray (22) showing its height (23) and the fluted edge (26). Labels 17, 19, 21, 22, and 23 are shown.

Fig. 5. A side view of a tray (17) with a fluted edge (22). It contains a rectangular component (19) with a central slot (20). Labels 17, 19, 21, 23, and 26 are shown.

UNITED STATES PATENT OFFICE.

JOSEPH E. ROGERS, OF MAMARONECK, NEW YORK, ASSIGNOR TO DAYTON SCALE COMPANY, OF DAYTON, OHIO, A CORPORATION OF NEW JERSEY.

SCALE AND CHART THEREFOR.

Application filed April 8, 1925. Serial No. 21,576.

The present invention is directed to the provision of an improved scale which is particularly adapted for mixing and compounding purposes.

5 A further object of the present invention resides in the provision of a novel chart adapted for use in cooperation with a weighing scale, which chart is provided with one or a number of fields preferably successively 10 disposed in having weight indicating graduations designating the amounts of quantities and ingredients and also preferably having indicating data designating a substance or ingredient which is represented 15 by a particular weight field or fields. The chart furthermore may be provided with supplemental mixing instructions or other written information.

For a clear and complete understanding 20 of the objects and advantages of my improved construction of scale and of the charts for use in connection therewith reference may be made to the present practice in a household kitchen where various mixtures of food are concocted. The present practice in a kitchen of the average household is to utilize cook books, receipt books or written receipts, measuring vessels and appliances of various sorts and conversion 25 tables of comparatively rough accuracy. Scales are utilized only to a limited extent as most receipts call in part for quantities of substances defined by various liquid measures. As a result the average housewife in 30 mixing a comparatively simple mixture has to utilize not only a large number of books, tables and the like but also various containing vessels and measuring vessels. Furthermore, the housewife must be able to 35 interpolate various tables and convert liquid into dry measure, etc.

By utilizing the scale and the mixing charts which form the subject matter of the present invention this procedure is materially simplified. In place of utilizing cook 45 books, written receipts and the like, the housewife may be provided with a card index file containing a number of supplemental charts or cards. An individual card 50 or chart is provided for each receipt. This chart or card not only is provided with a list of the ingredients and instructions as to their use and mixing but also is provided with one or more weight fields, the lower

field being preferably arranged successively 55 and being graduated to define the relative amounts of various ingredients into a given mixture on a weight basis. For convenience the weight fields of the charts themselves are designated with the particular ingredient 60 represented by the particular weight field. Furthermore, the order or sequence of the fields on the chart determines the order in which ingredients are to be added to the mixture. The housewife after selecting a desired receipt, say, that of a cake, from the card file places the card or supplementary receipt chart in a weighing scale of novel form. After placing the mixing receptacle 65 upon the scale pan the weight of this receptacle is tared off and the housewife then merely observes the chart and adds the various ingredients in the order called for by the chart. The ingredients are added in the order set forth on the chart and their quantity is readily determined by the housewife 70 observing the correlation of the indicating hand of the scale and the particular fields and designating graduations on the charts 75 which relate to the particular ingredient being added to the mixing receptacle. In this way the mixing procedure is materially simplified, the use of large numbers of measuring vessels is done away with and comparatively complicated receipts can be made up 80 with very great accuracy.

In the drawings,

Fig. 1 is an elevational view of my improved household scale.

Fig. 2 is a transverse sectional view 90 through the chart housing showing the interior arrangement of the parts.

Fig. 3 is a section taken on line 3—3 of Fig. 2.

Fig. 4 is a section taken on line 4—4 of 95 Fig. 2.

Fig. 5 is an end view of the chart housing showing the card receiving slots, the view being taken substantially on line 5—5 of Fig. 2 and looking in the direction of the arrow. 100

Fig. 6 is an assembly view showing the household scale mounted upon a common base with a unit adapted for driving various other household utensils.

In more detail the scale to which my invention is shown as here applied is of the conventional fan type. It comprises a base 105 having the usual scale beam 11 supported

thereon with a platform or platter 12. 13 is a tare beam and poise arrangement which can be used for taring off the weight of a receptacle such as 14. 15 is the indicator of the scale which is controlled by the automatic counterbalancing mechanism 16. The chart housing 17 is of the general form used in scales of this type and is arranged to suitably support a fixed weight chart 18. (See also Figs. 3 and 4.) In order to provide for the reception of supplemental charts which carry directions and graduations to guide the user of the appliance in mixing various receipts the chart housing is provided with an opening at one end and preferably this opening is provided with a tapered guiding member 19 which facilitates the introduction of the cards into the chart housing. The cards upon which the various receipts and directions are printed are shown in front view in Fig. 2. These cards preferably comprise a central card portion 20 and a rim portion 21, the rim portion being in the form of a beading which stiffens the edges of the cards and prevents the abrasion and mutilation of the same. The rim portion further serves to cooperate with guiding slots 22 (see Fig. 4), which guiding slots are preferably disposed in bracket members 23 fixed to the chart housing. The arrangement of the guide slots 22 is such that the inserted cards 20 with their rim portions 21 pass back of and clear of the indicator 15 so that this indicator can freely traverse the supplementary chart 20 when the same is in position in the scale. The use of the device will be obvious. Assume that it is desired to mix a particular sponge cake. The user of the appliance turns to a card file and selects the desired card giving the receipt for the particular cake mixture which is intended to be made. This receipt card is then inserted in the scale. In addition to providing written directions as to the method of compounding the receipt the receipt card carries a graduation line 26 with a number of graduations such as 27 thereon. The first operation is to adjust the tare poise 13 to tare off the receptacle. The indicator now is at zero at the zero graduation on the chart 20. The user first adds beaten eggs to the receptacle 14 until the indicator stands at the right hand graduation adjacent the "beaten eggs" designation on the chart. Following this granulated sugar is added until the granulated sugar field on the chart is traversed by the indicator. The operator then observes that the next ingredient symbol is not written out but is merely an initial. By reference to the chart this symbol O is ascertained to call for orange juice. Orange juice is then added until the indicator has traversed this particular field. The

succeeding operations are carried out in a like manner until the complete mixture has been added to the receptacle. It is obvious that any desired mixing directions can be printed on the direction chart. 70

It is also obvious that the scale can also be used for regular weighing operations. When this is desired the user removes any supplementary chart which may be in the scale whereupon the regular weight chart 18 75 will be exposed to view.

The supplemental chart 20 which carries the successive weight fields which are delimitated by the graduations 27 is preferably located in the chart housing by a suitable stop or abutment member 30. The location of this abutment member is such that the zero graduation of the supplementary chart is disposed in alignment with the zero point of the fixed weight chart when the supplementary chart or card is pushed in to its fullest extent so as to abut against part 30. 80

While I have described the present invention particularly with respect to its use in a household it will be understood that the device also finds application in commercial uses where there is a mixing or compounding of any substances or ingredients. For example the device may be utilized for secret compounding inasmuch as the supplemental charts of themselves do not bear any direct weight indications. For secret compounding the fixed weight chart preferably would be done away with. Also the tare graduations would be dispensed with and preferably a fixed tare arrangement would be provided. The user of the device would then be unable to tell the weight equivalents of the ingredients of the mixture being compounded. 95 100 105

Other modifications and uses of the device herein disclosed will readily be apparent to those skilled in the art.

What I claim is:— 110

1. A weighing scale of the automatically counterbalanced type having a chart housing, a weight chart therein and a cooperating weight indicator and having in combination therewith a supplementary chart provided with progressive graduations of weight designating graduations and data thereon indicative of successive increments of various kinds of substances to be weighed in one operation. 115 120

2. A weighing scale of the automatically counterbalanced type having a chart housing, a weight chart therein and a cooperating indicator and having in combination therewith a supplementary chart provided with progressive weight designating fields each field having associated therewith data instructive as to the kind of commodity or substance represented by a particular field, the aforesaid indicator being adapted to 125 130

successively traverse the various fields of the supplementary chart and cooperate with the weight designation thereon.

3. A weighing scale of the automatically counterbalanced type having an indicator and provisions for removably and replaceably receiving supplementary formula charts in cooperative relation to said indicator.

10 4. A weighing scale of the automatically counterbalanced type comprising weighing means, a displaceable weight indicator and a chart housing having means for insertably receiving and locating supplementary direction charts in cooperative relation to said indicator.

20 5. A weighing scale of the automatically counterbalanced type comprising in combination with a displaceable indicator, a chart housing guide means therein to guide a supplemental and insertable chart into position to be traversed by the said indicator, and a supplemental chart supported by said guide portions and provided with a successive series of weight fields each field being separated from another by a graduation and direction data associated with each of fields for designating a particular commodity or substance the weight of which is represented by the correlated field and the weight graduations.

25 6. A weighing scale having a variable displaceable indicator, an insertable chart, means upon said scale for receiving and locating said insertable charts in juxtaposition

to said indicator, each said insertable chart being provided with a successive series of weight designating fields, each field being separated from an adjacent field by a graduation weight and direction data associated 40 with each field for designating a commodity or substance the weight of which is represented by the corresponding weight field.

7. A weighing scale having a displaceable indicator, a main weight chart, and a supplemental chart and means for guiding said supplemental chart into position between the main weight chart and the indicator.

45 8. A weighing scale having a displaceable indicator and a fixed weight chart, a manually removable supplementary chart having weight designating graduations thereon including a zero or starting graduation, means for guiding said supplemental chart into position intermediate the main 50 fixed weight chart and the indicator, and means comprising an abutment for relatively locating the zero graduation of the supplementary chart in alignment with the zero graduation of the fixed weight chart. 60

9. A weighing scale of the automatically counterbalanced type having an indicator and provisions for freely releasably, replaceably, receiving a supplementary formula chart in cooperative relation to said indicator.

In testimony whereof I hereto affix my signature.

JOSEPH E. ROGERS.
